ACCELERATING CONTROL FOR
CARBURETORS

Charles R. Snyder, Miami Beach, Fla.

Application September 6, 1940, Serial No. 355,655

5 Claims. (Cl. 261—34)

This invention relates to an improved carburetor for delivering vaporized or gaseous fuel mixtures to the cylinders of internal combustion engines, the present application being a continuation-in-part of my prior application, Serial No. 299,899 filed October 17, 1939.

It is an object of the present invention to provide a carburetor which will effect the delivery of a vaporized fuel mixture to the cylinders of an associated engine to produce efficient combustion therein under all conditions of engine or motor vehicle operation.

One of the chief difficulties encountered in the operation of a motor vehicle is that of obtaining rapid and efficient speed acceleration. When an accelerator control is sharply depressed to obtain a sudden increase in the speed of a motor vehicle, the ordinary carburetor quite frequently does not quickly respond to the speed demand, or the associated engine may choke or back-fire.

In accordance with the present invention, my improved carburetor is provided, in the vaporized fuel outlet thereof at a point in advance of its throttle valve, with an auxiliary or supplemental liquid fuel inlet, the latter providing for a limited and automatically controlled inflow of a regulated quantity of liquid fuel directly into the vaporized fuel outlet passage of the carburetor, this action occurring when a demand for a sudden increase or acceleration in the speed of the associated engine is created by accelerator operation, and such supplemental feeding of liquid fuel into the carburetor for a predetermined period providing additional fuel for the required engine acceleration.

Another feature of the present invention is the provision of an improved fluid-actuated timing mechanism which is responsive to manual actuation for the purpose of effecting the opening of a control valve used in injecting supplemental quantities of liquid fuel into the outlet throat of the carburetor, said timing mechanism being such that after its operation has been initially manually actuated, said mechanism will automatically return to its normal position, after a predetermined interval of time, to seat the supplemental fuel-supply controlling valve.

Further objects and advantages of the invention will be in part obvious and in part pointed out hereinafter.

In the accompanying drawings:

Fig. 1 is a vertical sectional view taken through a carburetor formed in accordance with the present invention;

Fig. 2 is a fragmentary view in side elevation disclosing the lower or outlet portion of the carburetor and also disclosing the supplemental fuel flow controlling valve and the timing mechanism employed in controlling the operation of said valve;

Fig. 3 is a vertical sectional view on the plane indicated by the line III—III of Fig. 2;

Fig. 4 is a detail vertical sectional view taken 10 through the primary fuel-admitting valve of the carburetor;

Fig. 5 is a horizontal sectional view on the line V—V of Figs. 1 and 4;

Fig. 6 is a detail vertical sectional view taken 15 through the supplemental fuel admitting valve and its associated actuating mechanism and disclosing said valve in its open position;

Fig. 7 is a similar view disclosing the supplemental fuel admitting valve in its position of 20 closure;

Fig. 8 is a similar view through a modified form of timing mechanism used in controlling the actuation of the supplemental fuel admitting valve;

Fig. 9 is a side elevational view disclosing the 25 actuating levers for operating the mechanism set forth in Fig. 8;

Fig. 10 is a detail vertical sectional view taken 30 through a modified form of cylinder for the timing mechanism.

The carburetor illustrated in the accompanying drawings is of the type disclosed in my aforesaid patent application, since the specific improvements hereinafter set forth are particularly, though not necessarily, useful and applicable to a carburetor of the type therein disclosed. It will be understood at this juncture, however, that, with respect to the improved mechanism for introducing supplemental quantities of liquid fuel into the carburetor, many other different types of carburetors may be employed.

As shown in the drawings, the numeral 1 designates the outer casing of the carburetor, said 45 casting comprising substantially circular upper and lower metallic sections 2 and 3 respectively, the said sections being spaced by a ring or annulus 4, which may be of a transparent or translucent material, if desired. The upper and lower edges of the ring 4 engage with gaskets 5, and clamping bolts and nuts 7, spaced at circumferential intervals, are utilized to couple the sections 2 and 3 and the ring 4 in operative assembled relationship.

Formed with the upper section 2 is an air 55 inlet 6 having a flared inlet end and a narrow 60 outlet end, the inlet end being positioned to receive air from the front of the carburetor and the outlet end being positioned to project forward of the carburetor.

admitting conduit 8, the latter having a curvilinear form terminating at one end in an air inlet 9 of uniform diameter, the interior of the conduit gradually increasing in diameter as it extends inwardly and downwardly toward the vaporizing chamber 10 of the carburetor.

Normally occupying the inlet 9 of the conduit is a disk-shaped shutter or plunger 11, the latter having its under surface formed so that it is substantially convex, while its upper surface may be flat, the diameter of the shutter being slightly less than that of the inlet 9. Extending upwardly from the shutter is an arcuate arm 12, which at its upper end is adjustably connected, as indicated at 13, to the outer extremity of an irregularly shaped arm 14. The inner end or hub of the arm 14 is fixed to a transversely extending shaft 15, arranged above a stationary valve barrel 16. A spiral spring 17 has its outer end connected as at 18 with an intermediate portion of the arm 14, while the inner end of the spring 17 may be suitably fastened to a stationary part of the carburetor casing, such as the top of the barrel 16, which is formed with bearings for the reception of the shaft 15. The tendency of the spring 17 is to maintain the shutter or plunger 11 in the inlet 9 of the conduit 8, and in contact with a stop member, such as that indicated at 19.

The valve barrel 16 is provided with an axial bore 20 for the reception of a rotatable valve 21, which constitutes the primary fuel admitting valve of the carburetor. Also formed in the barrel 16 in spaced but parallel order with the bore 20 is a fuel passage 22, the upper end of the latter communicating with a pipe line 23 leading to a suitable source of fuel supply. Ordinarily, this source comprises the fuel pump of an associated automotive engine, although any other equivalent means may be employed just as long as the liquid fuel is delivered under pressure or gravity head to the passage 22.

The lower end of the fuel passage is in communication with the bore 20, as shown in Fig. 4, by means of a restricted, horizontally disposed, arcuate slit or slot 24. It will be noted in Figs. 4 and 5 of the drawings, that this slit or slot is disposed in registration with a pocket or recess 25 formed in the lower end of the valve 21. With this valve positioned, as shown in Figs. 4 and 5, liquid fuel travels from the passage 22, through the slit or slot 24 and into the lower end of the bore 20. However, by rotating the valve 21, the pocket or recess 25 may be moved either partly or completely out of registration with the slit or slot 24 so as to either restrict or fully preclude inflow of liquid fuel into the bore 20 through said slit or slot. This flow of fluid may be very minutely metered by the use of the construction disclosed so that precise proportion of the amount of air admitted into the vaporizing chamber 10 through the conduit 8 in relation to the amount of liquid fuel introduced into said chamber may be procured.

The rotation of the valve 21 may be obtained by providing its upper end with a beveled gear 26 which meshes with a gear 27 on the shaft 15. Since this shaft is rocked by the movement of the arm 14, which responds to unbalanced air pressures on the opposite sides of the shutter 11, a true relationship is established between the inflowing air and liquid fuel streams. With the use of this construction, as suction forces are created in the vaporizing chamber of the carburetor, the air shutter responds to such forces by traveling inwardly into the conduit 8 against

the resistance of the spiral spring 17. Since the diameter of the shutter is fixed, it follows that as the latter travels in an arcuate path into the tapering conduit 8, the free space between the peripheral edge of the shutter and the inner surfaces of the conduit gradually and progressively increases, thus responding to the volume of air entering the carburetor in order to provide means to measure and proportion the quantity of liquid fuel admitted to the carburetor in its different stages of operation. Since the air shutter is directly coupled with the fuel admitting valve and the latter moves proportionately with the movement of the air shutter, constant and definite proportions are maintained throughout all stages of carburetor operation in the relative volumes of air and liquid fuel admitted into the mixing chamber of the carburetor.

The lower end of the valve barrel or guide 16 is externally threaded for the reception of a sleeve 26'. Within the confines of the sleeve 26', the lower end of the barrel or guide 16 terminates in a reduced extension in which the slot 24 is formed. The sleeve 26' is formed with an aperture inwardly directed flange which receives and guides the lower end of the valve 21, and below this flange, the interior of the sleeve 26' is internally threaded as at 28 for the reception of an orifice nipple 30, the latter being provided with a vertical bore which approximately corresponds in diameter to that of the valve 21, the cut-out or recessed portion 25 of said valve stem providing a vertical opening for the descent of liquid fuel. The lower end of the nipple 30 terminates immediately above a rotatable fuel-disseminating disk 31, which is mounted horizontally in the mixing or vaporizing chamber 10 for rotation about a vertical axis of the carburetor. This disk is adapted to rotate at high speeds so that liquid fuel particles, released from the orifice nipple 30 and deposited in the center of the disk, will respond to its high rotational speeds and be released by centrifugal force from the peripheral edge of the disk in the form of a fine mist or spray traveling horizontally, tangentially or radially in a substantially horizontal plane from the edge of the disk toward the inner surfaces of the ring 4. The centrifugal forces applied to the liquid fuel droplets by the rapidly revolving disk, results in the mechanical disintegration of said droplets into extremely fine particles, forming a mist or spray. Through this mist or spray, air drawn into the carburetor is advanced and intimately combined therewith while in the chamber 10 to produce an efficient fuel mixture for consumption in the cylinders of an associated internal combustion engine.

In order to effect the support and rotation of the disk 31, there is fixed on the lower end of the sleeve 26' the inner race ring 32 of a ball bearing, the outer race 33 of said bearing being secured to the under side of a rotor plate 34. This plate supports the disk 31 for rotation in unison therewith by means of the vertically extending and circumferentially spaced pins 35. The top of the rotor plate 34 carries a plurality of circularly arranged vanes or buckets 36, which are disposed immediately below and in registration with the restricted outlets of a plurality of angularly and downwardly extending nozzle elements 37. These elements, as shown in Fig. 1, are carried by a ring 38, which has a threaded connection with the walls of a tubular extension 39, constituting the lower or outlet end of the conduit 8. Air thus traveling through the con-

designed to subsequently be received in said conduit 8, and the air entering the mixing chamber 10 through the nozzle elements 31 and which, because of their restricted construction, discharge air therefrom at high velocities in the form of restricted streams. While such air streams are traveling at their peak velocities, the same impinge the vanes or buckets 36 of the rotor 34, setting up high rotational speeds on the part of the said rotor and its suspended fuel disseminating disk 31.

The extension 39, as shown in Fig. 1, is formed with slots 40, which are normally closed by means of hingedly mounted arcuate strips or shutters 41, springs 42 being associated with the strips to normally maintain the latter in positions obstructing air flow through the slots 40. With the engine operating at low speeds, most of the air entering the carburetor through the conduit 8, will travel through the nozzle elements 31 before entering the mixing chamber 10, thus insuring the desired rotation of the disk 31 at lower engine speeds. As the speed of the engine increases and the volume of air entering the carburetor correspondingly increases, sufficient pressure will be built up in the extension 39 to effect either simultaneous or selective opening of the slots 40 in order to compensate for the increased volumes of air entering the carburetor. At all stages of operation, however, a sufficient amount of air is delivered to the nozzle elements to effect the rotation of the disk 31.

Projecting from the extension 39, immediately over the rotor plate 34, is a convex, ring-shaped baffle plate 43, which directs air entering the mixing chamber 10 by way of the slots 40 into paths indicated by the arrow a. Likewise, the diameter of the rotor plate 34 is considerably in excess of that of the disk 31 so that air entering the mixing chamber through the nozzle jets merges with the air stream introduced by way of the slots 40. The rapid air flow through the mixing chamber does not interfere with the centrifugal release of finely divided fuel particles through the peripheral edge of the disk 31. Below said disk, there is arranged a stationary baffle plate 44, which is supported in a horizontal plane by studs 45 carried by the casing section 3. The plate 44 is thus disposed above the carbureted fuel outlet 47, which latter is formed in the section 3. In this outlet, there is arranged the usual throttle or butterfly valve 48 fulcrumed at its center, as indicated at 49. A back-fire releasing opening 50 is formed in the upper section 2 of the carburetor casting and is normally closed by a spring pressed flat valve 51.

The carburetor above described is substantially that disclosed in my aforesaid copending application, Serial No. 299,899, with the exception that the valve 21 is rotatable in governing the admission of fuel into the carburetor, rather than linearly slideable, since I have found that the rotation of the primary fuel admitting valve embodies less friction in its operation and provides for a more accurate metering of the inflow of the liquid fuel than does the slideable type.

It is one of the purposes of the present invention to further improve my carburetor, particularly in the matter of rendering the same instantly and effectively responsive to demands for sudden increase in engine or vehicle speeds, that is, to provide sharp acceleration, such as that occasioned when a vehicle is being rapidly advanced in speed after being stopped, or when passing other vehicles moving in the same direction. To attain such acceleration, I provide for the introduction of a supplemental quantity

2,314,171 of liquid fuel after the engine has begun to run, and this supplemental fuel is caused of liquid fuel into the vaporized fuel outlet 41 of the carburetor at a point above the throttle valve 48. This supplemental feeding of liquid fuel into the carburetor takes place automatically with the normal operation of depressing the accelerator pedal, and a feature of my present invention is the provision of a timing mechanism by which the inflow of this supplemental fuel supply is terminated automatically when the engine attains the desired accelerated speed.

Therefore, in accordance with these ends, a T-fitting 52 is threaded into the side wall of the throat 47. This fitting is formed with a vertical bore having an enlarged valve-receiving upper portion 53, a somewhat reduced lower portion 54, and an intermediate tapering valve seat 55. Threaded into the lower portion 54 of said bore is a pipe coupling 56 carrying a fuel supply pipe 57, the latter being suitably extended to and joined with the pipe line 23, so that liquid fuel under pressure, or under a gravity head, will be positively delivered at all times to the lower portion 54 of the bore in the fitting 52. The latter is also formed with a restricted horizontally extending port 58, which leads from the seat 55 to the interior of the throat 47. A cylindrical valve member 59 is employed for controlling the supplemental flow of liquid fuel through the fitting 52 and into the throat 47. The tapered lower end of the valve 59 engages with the seat 55 and, when so normally positioned closes the port 58. The upper end of the fitting 52 is threaded for the reception of a cap 60, the latter being centrally apertured for the reception of a valve stem 61, arising from the member 59. The upper end of this stem is provided with a head 62, and surrounding the stem 61 and positioned between the upper surface of the cap 60 and the under surface of the head 62 is an expansion spring 63, the normal tendency of which is to elevate the valve 59 and uncover the port 58.

The spring 63, however, is normally depressed, and the valve member 59 maintained in its seated position, by means of the shorter arm 64 of a bell crank lever 65, the latter being fulcrumed as at 66 on the carburetor casing. This bell crank lever has its longer arm, as shown in Fig. 2, terminated in a collar 67, which movably surrounds a timing cylinder 68. The collar 67, in the form of my invention as disclosed in Figs. 2 and 3, is normally disposed slightly above a supporting bracket extension 69, which integrally and stationarily projects from the outer wall of the throat 47 of the carburetor casing. The upper end of the cylinder 68 is externally threaded for the reception of a closure cap 70 and, normally, the lower edge of the cap 70 engages with the collar 67 in order to maintain the bell crank lever 65 in such position that its shorter arm 64 will hold the valve member 59 in a seated position, closing the port 58. The lower end of the cylinder 68 has integrally formed therewith a head 71, in the outer portion of which is formed an annular seat for the reception of the lower convolutions of a helical spring 72, the upper convolution of said spring being engaged with the lower surface of the ring-shaped portion of the bracket extension 69. The spring 72 is of greater strength than the spring 63, and is aided by leverage, so that the spring 72 will overcome the strength of the spring 63 in maintaining the valve member 59 seated.

Slidably mounted within the timing cylinder 68 is a piston 73, the outer periphery of which has

but loose fitting engagement with the inner surfaces of the cylinder. The piston 73 is formed with a hub 74, said hub receiving the lower end of a stem 75, the latter being formed with a valve head 76. This head is normally positioned to occupy a tapered seat 77 formed in the under part of said piston in order to close a multiplicity of oil by-passing ports 78 provided in said head. The piston 73 is permitted to slide for a limited amount of movement on the lower end of the stem 75, this movement being controlled by means of a washer 79, carried on the lower end of the stem 75 and a coil spring 80, which surrounds the hub 74 and presses against the washer 79.

The upper end of the stem 75 passes through a stuffing box 81 formed in the cap 70 and at its upper end is pivotally connected as at 82, with the outer end of a link 83, the other end of said link being pivotally mounted as at 84 on a stationary part of the carburetor casing. Intermediately of its length, the link 83 has pivotally connected therewith as at 85, a depending link 86, and the lower end of this depending link is pivoted as at 87 to the outer end of a crank arm 88 which, in turn, is secured on the outer portion of the shaft 89 of the throttle valve 48. Also secured to the outer end of the shaft 89 is a second and longer crank arm 90, and to the outer end of the arm 90 there is pivotally connected the upper end of an actuating rod 91. This rod is actuated usually by means of a standard motor vehicle accelerator control, such as is diagrammatically illustrated in Fig. 3 at 92.

In the operation of this supplemental fuel admitting mechanism, it will be seen that when the motor vehicle operator sharply depresses the accelerator 92, or its equivalent, the rod 91 is moved upwardly in the direction indicated by the arrow B in Fig. 3. This movement rocks the shaft 89 of the throttle 48, moving the throttle to an open position in the throat 47, and at the same time elevates the link 83 in order to raise the stem 75 and the piston 73 in the timing cylinder 68. This upward movement of the piston 73, against the resistance of the oil or other fluid contained within the timing cylinder, creates suction forces in the bottom of the timing cylinder, below the piston 73, which result in upward sliding movement of the timing cylinder against the resistance of the spring 72, until the timing cylinder and the parts contained therein assume substantially the positions indicated in Fig. 6, wherein it will be noted that the bell crank lever, being freed from engagement with the cap 70, rocks under the energy supplied by the spring 63 to enable the valve member 59 to assume its open position uncovering the port 58. When the valve member 59 is thus unseated, motor fuel under pressure will be injected in limited amounts directly into the carburetor throat 47, where it is vaporized and admixed with the primary fuel mixture formed in the chamber 10 and carried into the engine cylinders. Preferably, the port 58 is located immediately above the throttle valve 48 so that it strikes this valve when injected into the carburetor and is spread over the surface of the valve for ready vaporization.

This injection of supplemental fuel is maintained for a predetermined interval of time, the interval being of sufficient duration to enable the engine to acquire maximum speed or acceleration, after which a supply of this supplemental fuel is automatically terminated, regardless of the fact that the operator of a motor vehicle may still

continue a position of depression of the accelerator control 92. The duration of this period of supplemental fuel injection may be varied by using springs 72 of different strength, by employing liquid of different viscosities in the timing cylinder 68, or by adjusting the clearance between the piston 73 and the inner walls of the cylinder 68. After the cylinder 68 has been elevated to its maximum or any intermediary position, the spring 72 expands, so that the liquid above the piston 73 is vacuum pulled by the descending cylinder to pass into the lower portion of the cylinder below the piston through the clearance provided between the piston and the inner cylinder walls. As the liquid thus bypasses the piston, the spring 72 is allowed to expand until the cylinder again assumes its fully lowered position as shown in Fig. 7. When so lowered, the cap 70 engages the collar 67 of the bell crank lever, causing the re-seating of the valve member 59. This may require any predetermined length of time, depending upon the acceleration properties of the associated motor under its normal load, as it is desirable to have supplemental injection of fuel for the entire period of acceleration.

This slow and timed descent of the cylinder 68 takes place when the piston 73 is held elevated by the vehicle operator pressing on the accelerator control 92. If the vehicle operator should release the control 92, in order to cease acceleration, the cylinder 68 rapidly or instantaneously returns to its lowered position, since the release of the accelerator control causes the cylinder 68 and associated piston 73 to move downwardly as a unit in response to the action of the spring 72. This action continues until the downward motion of the cylinder is stopped by contact of the cap 70 with the collar 67 of the lever 65, thus terminating the injection period of supplemental fuel. Should the operator continue depression of the throttle valve to a position beyond this point of contact, it is impossible for the cylinder 68 to lower beyond this point of contact with the bell crank lever 67 and stem 75. Therefore, the lowering of the stem 75 causes the piston 73 to press against the oil or other liquid confined in the space between the bottom of the cylinder and the piston 73. This pressure will cause the spring 80 to contract, thus exposing fuel by-pass ports 78, so that such liquid may pass freely from the bottom of the cylinder 68 to a position above the piston 73 with a minimum of resistance to the downward motion of the stem 75. After the stem 75 and the piston 73 arrive at a stationary position in their downward motion, the spring 80 causes the valve head 76 to seat, closing the by-pass port 78 instantaneously, and therefore any subsequent opening of the throttle valve 48 by the operator of the vehicle will cause an opening of the valve 52 as previously described.

In the form of my invention as disclosed in Figs. 8 and 9, a somewhat different method or principle is used in governing the operation of the timing cylinder. In this form, the timing cylinder 68a is slidably positioned in the ring of the bracket extension 69a. A coil spring 72a of the contractible type is connected with the under portion of the bracket extension 69a and the cylinder 68a, the normal tendency of said spring being to elevate the timing cylinder. The top of the timing cylinder 68a carries a cap 70a, upon the top of which rests the collar 67a of a bell crank lever 65a. One arm of the lever 65a engages a head provided on the upper end of a stem

61a of a valve member 59a. A spring 63a surrounds the stem 61a and normally tends to maintain the valve member in an elevated or unseated position within the fitting 52a. Since the spring 12a is stronger than the spring 63a, it would seem that the valve member 59a is normally maintained seated even though influenced by the relatively weaker spring 63a.

Arranged in the cylinder 68a is a piston 73a. The hub 14a of this piston slidably receives the lower end of a stem 75a, which projects upwardly through a stuffing box 81a provided in the cap 70a. The upper end of the stem 75a is connected with a link 83a pivoted as at 84a. Intermediately the link 83a is connected with a second link 86a. The lower end of the link 86a is pivotally connected with a short crank arm 88a fixed on a throttle valve shaft 89a. The shaft 89a carries a crank arm 90a which is adapted to be rocked by a control means united with an accelerator pedal.

In the operation of the form of the timing mechanism disclosed in Figs. 8 and 9, when the accelerator control is fully depressed, the stem 75a is moved in a downward direction carrying with it the piston 73a, thereby producing pressure on the liquid in the bottom of the cylinder, which causes the timing cylinder 68a to be moved downwardly against the resistance of the spring 72a. This tends to move the cap 70a away from the collar 67a so that the bell crank lever 65a will be rocked to release the spring 63a and allow the valve member 59a to be unseated. As in the previous form of my invention, following the unseating of the valve member 59a, the spring 12a exerts its pressure and forces oil, or other fluid, from the bottom of the cylinder 68a through the clearance spaces provided between the piston 73a and the inner walls of the cylinder, effecting a slow, definite return of the cylinder to its normal position. Sudden release of the accelerator pedal causes an accelerated return of the timing cylinder to its normal position.

To control the extent of opening or unseating of the valve member 59, the longer arm of the bell crank lever 65, immediately beneath the fitting 52, may be provided with a set screw 95. This set screw engages the bottom of the fitting, thereby limiting the rocking movement of the bell crank lever and, accordingly limiting the extent of upward movement of the valve member 59. Similar control is indicated at 95a in the form of my invention depicted in Fig. 8.

In view of the foregoing, it would seem that the present invention provides novel, simple and efficient means for effecting the direct introduction for a predetermined period of time of a supplemental quantity of liquid fuel into the carburetor of an internal combustion engine. The introduction of this supplemental fuel takes place only during critical stages of engine operation, namely, when it is desired to effect the rapid acceleration and speed of a motor vehicle from a standing start to a given driving speed or, more particularly, when passing motor vehicles traveling in the same direction at highway speeds. It will be observed that this injection of supplemental fuel takes place in an automatic manner without any attention on the part of the vehicle operator other than that customarily used in operating accelerator pedals. When the accelerator pedal is depressed either fully or in part for sharp acceleration, the supplemental fuel is injected into the vapor outlet of the carburetor. This injection takes place only for a definite 75

time limit, even though the vehicle operator continues to maintain the accelerator pedal in an advanced position. This period or interval of supplemental fuel injection is determined by the working performance of the engine associated with the carburetor, some engines requiring a greater period than others to obtain desired accelerated speeds. The apparatus, however, is readily adjustable and adaptable to meet the requirements of these different supplemental fuel injection periods. If at any time the operator should release the accelerator pedal, the injection period is instantly terminated due to the downward motion of the cylinder and the piston as a unit, as induced by the spring 72 until supplemental injection of fuel is stopped. The apparatus is thus one of automatic operation and does not necessitate manual attention, so that there is no danger of excess fuel consumption by reason of the employment of the supplemental fuel injector nor any likelihood of an engine becoming fouled or unduly burned by excess quantities of a fuel supply.

Narrow ported breather vents 97 are carried by 25 the closure cap 70 of the cylinder 68 to prevent undesired vacuums from being formed in the upper portions of the cylinder. Such a breather vent is also provided for the cylinder 68a disclosed in Fig. 8.

30 In Fig. 10, in lieu of using the open vent, I employ a closed or dome-like fitting which may be employed for similar ends. While I prefer to mount the supplemental fuel injector in the outlet throat of the carburetor, as disclosed in Fig. 1, it will be obvious to those skilled in the art that 35 the same may be disposed in other locations with respect to the carburetor casing. My improved fluid-actuated timing mechanism provides for a determinative period of supplemental fuel injection by its regulation of the reflex action of the 40 return springs 72 and 72a, producing a more sensitive and positive control than can be obtained with the use of spring action alone.

What is claimed is:

- 45 1. In mechanism for introducing supplemental quantities of fuel to a carburetor during periods of engine acceleration, a line leading from a source of fuel and communicating with the interior of the carburetor, a normally closed control valve in said line, means for actuating said valve, said means having a motion transmitting member, a bracket, a fluid-receiving cylinder mounted for sliding movement in said bracket, resilient means for yieldably resisting movement of said cylinder in one direction relative to said bracket to cause said member to open said valve, said cylinder being moved by said resilient means to effect the closing of said valve, a piston having a passage extending therethrough mounted for longitudinal movement in said cylinder, said piston having a valve seat formed thereon, a piston rod connected to said piston, said connection permitting limited relative movement between said rod and piston, a valve carried by said piston rod and normally engaging said seat to prevent fluid flow through the passage in said piston, and motion transmitting means connecting said piston rod and the throttle valve of said carburetor, movement of said throttle toward an open position serving to move said cylinder in opposition to said resilient means, movement of said throttle in the opposite direction serving to move the valve on the piston rod away from the seat on said piston.
- 50 2. In mechanism for introducing supplemental

quantities of fuel to a carburetor during periods of engine acceleration, a line leading from a source of fuel and communicating with the interior of the carburetor, a control valve in said line, spring means for moving said valve to an open position, motion transmitting means for moving said valve in opposition to said spring, support means adjacent to the carburetor, a liquid-receiving cylinder mounted for sliding movement in said support means, resilient means yieldably resisting movement of said cylinder in one direction in said support to cause said motion transmitting means to release said valve whereby it will open under the influence of said spring, said resilient means moving said cylinder in the other direction to cause said valve to move in opposition to said spring, a piston having a passage extending therethrough positioned for sliding movement in said cylinder, a piston rod connected with said piston, valve means actuated by said rod for controlling the flow of liquid through the passage in said piston, and motion transmitting means connecting said piston rod with said throttle valve whereby said cylinder will be moved in opposition to said resilient means to effect the opening of said control valve when said throttle is opened, the movement of said cylinder by said resilient means to close the control valve being retarded when said throttle is held open and simultaneous with the closing of the throttle when the latter is closed within a short time interval after being opened.

3. In mechanism for introducing supplemental quantities of fuel to a carburetor during periods of engine acceleration, a line leading from a source of fuel and communicating with the interior of the carburetor, a valve of the quick opening and closing type disposed in said line, means for controlling the operation of said valve, said means having a motion transmitting member, a bracket, a fluid-receiving cylinder movably mounted on said bracket, resilient means for yieldably resisting movement of said cylinder in one direction relative to said bracket to cause said member to open said valve, said resilient means moving said cylinder in the opposite direction to effect the closing of said valve, said valve being retained in a fully open position until the final stage of movement of said cylinder in the latter direction, piston means positioned in said cylinder for longitudinal movement, a piston rod connected with said piston, the connection being such as to permit limited movement therebetween, said piston having a passage extending therethrough, valve means carried by said rod, and motion transmitting means connecting said rod and the throttle valve, movement of the latter to an open position serving to move said cylinder to open the valve in said line, movement of said throttle in a reversed di-

rection serving to open the passage in said piston.

4. In mechanism for introducing supplemental quantities of fuel to a carburetor during periods of engine acceleration, a line leading from a source of fuel to said carburetor, a body connected in said line, said body having a valve seat, valve means disposed for sliding movement in said body toward and away from said seat to control fluid flow through said line, spring means normally tending to move said valve away from said seat, a pivoted lever disposed for engagement with said valve to move the same in opposition to said spring means, means for moving said lever to effect opening and closing movements of said valve, said means comprising a liquid-receiving cylinder, means for movably supporting said cylinder adjacent to a portion of said lever whereby the latter will be engaged and moved by the former upon movement thereof, resilient means for moving said cylinder in one direction, piston means slidably mounted in said cylinder, valve-controlled port means in said piston to permit unrestricted movement thereof in one direction in said cylinder, and means connecting said piston to the throttle of said carburetor, movement of said throttle to an open position serving to move said lever to open said valve, said resilient means moving said cylinder into engagement with said lever to close said valve.

5. In mechanism for introducing supplemental quantities of fuel to a carburetor during periods of engine acceleration, a line leading from a source of fuel to said carburetor, a body connected in said line, said body having a valve seat, valve means disposed for sliding movement in said body toward and away from said seat to control fluid flow through said line, spring means normally tending to move said valve away from said seat, a pivoted lever disposed for engagement with said valve to move the same in opposition to said spring means, a cylinder, means supporting said cylinder for longitudinal movement, a lost motion connection between said cylinder and said lever, a piston disposed in said cylinder for sliding movement, a rod connecting said piston to the throttle of said carburetor, whereby movement of said throttle toward an open position will effect movement of said cylinder, resilient means for returning said cylinder to normal position, valve means on said piston for controlling the rate of return movement of said cylinder, the initial movement of said cylinder in response to the movement of said throttle effecting movement of said first mentioned valve to an open position, said valve remaining fully open until the final stage of movement of said cylinder to normal position.

CHARLES R. SNYDER.
